United States Patent Office.

PETER GEISER, OF WAYNESBOROUGH, PENNSYLVANIA.

Letters Patent No. 94,592, dated September 7, 1869.

IMPROVEMENT IN SAWING-MACHINE.

The Schedule referred to in these Letters Patent and making part of the same.

To all whom it may concern:

Be it known that I, PETER GEISER, of Waynesborough, in the county of Franklin, and State of Pennsylvania, have invented a new and useful Improvement for Gauges and Saw-Tables; and I do hereby declare that the following is a full, clear, and exact description of the same, reference being had to the annexed drawings, making part of this specification, in which—

Figure 1 is a plan of a gauge;

Figure 2 is a vertical section of the same;

Figure 3 is a section of the oscillating and extension arms;

Figure 4 is a section of one of the adjustable prick-points;

Figure 5 is an elevation of an adjustable saw-table.

Figure 6 is a section of the same;

Figure 7 is an elevation, showing the mechanism for adjusting the hinged leaf of the table;

Figure 8 is a plan of a gauge, adapted for a flat table;

Figure 9 is a section of the extension-arm of the same, in line $x x$, fig. 8;

Figure 10 is a plan of a gauge, adapted for cutting above the saw; and

Figure 11 is an elevation of the same.

The same letters in all the figures indicate indentical parts.

My improvement relates to tables for circular saws, and to gauges for the same, by means of which the boards may be cut to lengths, bevelled and cross-cut at regulated intervals, at one handling of the board.

In the annexed drawings—

A is the top of the table, hinged at one end to the frame B, and to which is attached a hinged leaf, A', the saw being placed in the crack between the two leaves. The distance to which the teeth may be made to project above the table is regulated by the following mechanism:

The loose end of the top A rests upon a frame, C, sliding in vertical grooves in the legs of the table. The crank-rod D is attached by journal-boxes to the frame C, and its lower end has cut upon it the thread of a screw, which passes through a nut in the cross-brace B of the table-frame B. By turning the crank, the end of the top A may be raised or depressed, as desired.

The hinged leaf A' is supported at its outer edge upon the rack-bars E E, hinged thereto. The rack-bars are operated by the pinions E', upon the shaft E'', turning upon journals in boxes upon the main frame.

A notched ratchet-plate, E'', is attached to the frame, the shaft E'' passing through it; the spring lever E' is fastened to the end of the shaft E'', and it may be used to turn the shaft, by releasing the lever from the notches in the plate E''. When the lever is released, the tension of the spring will engage

it with one of the notches, and hold the table-leaf A' at any desired angle.

The gauge shown in figs. 1, 2, 3, and 4, is particularly adapted for use in connection with the hinged table-leaf. It is attached to a frame, having a triangular transverse section, as clearly shown in fig. 2, so that the upper surface may set close to the saw, and its edge be at the same level with the top A of the table. It is attached to the leaf A' by a tongue, f, fitting into a longitudinal groove, a, across the face of the leaf A', in such manner that its position may be adjusted, as desired.

G is an oscillating arm, pivoted to the frame F, and having an index arm, G', swinging in a segmental slot, through which passes a clamping-screw. This segment may be graduated, as shown in fig. 1.

On the oscillating arm G is an extension-arm, G'', slotted longitudinally, and attached to a groove in the form of an inverted T, in the arm G, as shown in fig. 3, by a clamping-screw, G'.

On the extension-arm are two swinging stops g, which serve to gauge the length of the pieces to be sawed into certain lengths. When the stop on the outer end of the arm G'' is used, the other may be turned on its pivot, so as to be out of the way. By means of the oscillating arm used as a gauge, the pieces may be cut to a certain length, either square upon the ends or at any requisite bevel.

H H are segmental slots, to receive the adjustable spring prick-points H', the elasticity of which permits them to be pressed by the pressure of the piece to be cut below the surface of the table, so as not to interfere with the proper disposition of the piece to be sawed.

The gauge I is intended for use with the oscillating arm G. By removing the extension-arm G'', and attaching it by the clamp-screw i, and by a screw passing through the eye i', the arch in the gauge passes over the saw. This gauge is especially designed for use in cutting kerfs part way through a board, at regular distances, for dovetailing or cutting gains or slots.

The adjustable spring-points i'' must be so set that they may, when they enter one kerf, form a guide to determine where another is to be cut. When coming in contact with the plain surface of the board, they will yield to its pressure, so that by using as many of the spring-points as may be needed, and by reversing on the boards, a series of kerfs may be cut at regulated distances. In cutting such kerfs, the table A must be raised, so that the teeth of the saw will pass only part way through the board. The oscillation of the lever G will permit the arched gauge to be set at any required angle. In fig. 8 I have shown a gauge adapted for use upon a table where the top is flat.

K is the frame, having on the under side a cleat, sliding in a groove in the top of the table, so that the gauge may be moved as required.

L is an oscillating arm, turning on a stud-pin passing through a slot, as shown at l. The slotted brace L' is pivoted to the arm L, and through the slot passes a guiding stud-pin. This arrangement allows the guide to be shifted, so as to cut the end of the board square, or to cut a bevel either entirely across or partly across the end of the board, according to the required form.

On the sliding extension-arm L², attached to the arm L by a slot and clamping-screw, is an oscillating stop, L³, which may be used when the boards are to be cut to a given length, or turned to the opposite side, to be out of the way of the board.

M is an oscillating adjustable arm, turning upon a stud-pin, m, attached to the frame K, passing through a longitudinal slot, and secured by a clamping-screw passing through a segmental slot in the frame at m'. The edge of the arm is bevelled, as shown. By means of these gauges, boards may be cut to a uniform size and shape, as required.

What I claim as my invention, and desire to secure by Letters Patent, is—

1. The combination of the hinged leaf A', rack-bar E, pinions E¹, shaft E⁴, notched plate E², and spring-lever E³, arranged to operate substantially as set forth.
2. In combination with the top A, frame C, and crank D, for elevating one end of the top, the hinged

leaf A', and the mechanism for adjusting it, substantially as set forth.

3. The frame F, for supporting the gauge, when constructed in the form of a triangle, and used in combination with a hinged leaf, substantially as set forth.

4. The combination of the oscillating arm G, brace G¹, extension-arm G², and hinged stops g, with the slotted frame F, substantially as set forth.

5. The frame F, constructed with concentric segmental slots H, in combination with elastic spring prick-points H¹, arranged to operate substantially as set forth.

6. In combination with the oscillating arm G, the arched guide I, constructed and arranged substantially as set forth.

7. In combination with the frame K, the oscillating slotted arm L and slotted brace L¹, arranged substantially as and for the purpose set forth.

8. The last above-recited parts K, L, and L¹, in combination with the adjustable extension-arm L² and stop L³, substantially as set forth.

In testimony whereof, I have signed my name to this specification, in the presence of two subscribing witnesses.
